PRESSING APPARATUS

Archie O. Long, Kansas City, Mo.

Application May 15, 1933, Serial No. 671,119

15 Claims. (Cl. 68—9)

My invention relates to a garment pressing apparatus and has for its principal object to provide a machine capable of large production of high quality work showing no overlaps or wrinkles in 5 the finished garment.

It is also an important object of the invention to press an entire right front half of one garment and the entire left half of a second garment in one pressing operation.

10 Other important objects of the invention are to provide for fewer adjustments of the garment being pressed, to provide adjustment for accommodating the machine to various size garments, to provide for substantially automatic press operation, and to afford safety to the operators of the machine.

In accomplishing these and other objects of the invention, I have provided improved details of structure, the preferred form of which is illustrated in the accompanying drawings, wherein:

20 Fig. 1 is a perspective view of a pressing apparatus embodying the features of my invention and particularly designed for pressing shirts, coats, summer suits and similar garments.

25 Fig. 2 is a vertical longitudinal sectional view through the portion of the machine for pressing the entire body of a shirt.

30 Fig. 3 is a similar vertical longitudinal sectional view through the portion of the machine for pressing the cuffs, collar and yoke gussets of the shirt.

35 Fig. 4 is a cross sectional view illustrating the right and left front pressing bucks in position to be moved into pressing engagement with the ironing head.

Fig. 5 is a similar view showing the back pressing buck in position to be moved into pressing engagement with the ironing head.

40 Fig. 6 is a detail vertical sectional view through the tail clamp and its supporting mechanism.

Fig. 7 is a plan view of the shirt body pressing turret showing the back pressing buck being rotated from the ironing head and the front pressing bucks being moved into position under the 45 ironing head, parts of the bucks being broken away to better illustrate the construction of the machine.

Fig. 8 is an enlarged vertical sectional view through one of the back pressing buck sections, 50 particularly illustrating the method of withdrawing moisture from the pad of the buck and showing the bridge plate for covering the space between the sections of the buck.

55 Fig. 9 is a detail sectional view through the turret actuating cylinder and valves controlling ex-

haust and air supply thereto and exhaust from the press actuating cylinder.

Fig. 10 is an enlarged detail sectional view on the line 10—10, Fig. 7.

Fig. 11 is an enlarged detail perspective view of 5 the collar and band clamp mechanism.

Fig. 12 is a detail side elevational view of the lever mechanism controlling operation of the collar and neck band clamp.

Fig. 13 is a similar view partly in section showing the mechanism for drawing the neck band into clamping engagement with the neck band blocks.

Fig. 14 is a plan view of the cuff, collar, yoke and gusset pressing bucks, showing shirts applied thereon.

Fig. 15 is a cross section through one of the body pressing bucks showing the clamp for securing the covering material.

Fig. 16 is a detail perspective view of an end 20 of one of the clamps.

Fig. 17 is a detail view of one of the gusset pressing bucks.

Referring more in detail to the drawings:

1 designates the frame of the machine, which 25 includes a base member 2, pairs of vertical posts 3, 4 and 5, 6 and a header member 7.

The base 2 includes right angularly extending portions 8, 9, having horizontal webs 10 and side flanges 11 and 12 for spacing the webs from the 30 floor.

The vertical posts 4, 5 and 6, 7 and a supplemental post 13 comprise cylindrical shafts having reduced threaded ends 14 and 15 forming spaced shoulders for engaging the webs 10 and 35 the lower flange of the header member 7, respectively.

The header member 7 also includes right angularly extending portions 16 and 17 having substantially the same length as the complementary 40 portions of the base member and comprise I-beam members having vertical webs 18 and horizontal flanges 19 and 20.

The pairs of posts 3, 4 are supported on the right angular portion 8 of the base member and the posts 5, 6 on the right angular portion 9, while the supplemental post 13 is supported adjacent the junction of the right angular portions in parallel relation with the pairs of posts 5, 6.

The lower reduced ends 14 of the posts extend 45 through openings 21 in the webs 10 and through aligning openings 22 formed in transverse bars 23 that reinforce and stiffen the webs 10.

The shoulders at the lower ends of the posts are 50 retained in engagement with the webs 10 by nuts 55

24 threaded on the lower reduced ends 16, as clearly illustrated in Fig. 2.

The upper ends 15 of the posts extend through tubular brackets 25 carried by the web portions 18 5 of the header so that the lower flanges 20 of the header rest on the upper shoulders and are retained thereagainst by nuts 26 threaded on the upper ends of the posts and engaging against the upper flanges 19.

10 The pairs of posts 3, 4, including the header portions 16 and base portion 8 form a supporting structure for the shirt body pressing mechanism while the posts 5, 6, including the header portion 7 and base portion 8 form a similar supporting 15 structure for the cuff, collar, gusset and yoke pressing mechanism later described.

In carrying out my invention, I provide for 20 pressing the entire left front half of one shirt and the entire front half of a second shirt, while the back of a third shirt is being arranged on the back pressing buck. Then when the back of the third shirt is being pressed, the right front half and the left front half of the first and second shirts are being prepared for the pressing 25 operation.

It is thus apparent that the entire body of one shirt is pressed upon the equivalent of two actuations of the press.

In order that this may be readily accomplished, 30 I provide separate bucks for the back and fronts of a shirt and mount them on a turret so that while the back of a shirt is being pressed under the ironing head, the operator is placing shirts in position on the front pressing bucks.

35 The body pressing bucks are mounted on a turret 27 that is rotatably mounted on the post 3, as now described. The turret 27 includes a cylindrical hub 28 rotatably mounted on the shaft 3 and having its lower end resting on the upper face 40 of the web 10, while its upper end is engaged by a collar 29 that is fixed to the post as best illustrated in Fig. 2. Extending upwardly and outwardly from the hub 28 at a point spaced from its lower end are arms 30 and 31 which cooperate 45 with similar arms 32 and 33 extending from the upper end of the hub for supporting vertically arranged bearing sleeves 34 and 35 in spaced relation to the hub.

50 Mounted in the respective sleeves 34 and 35 are the supporting structures for the front and back pressing bucks 36 and 37, respectively. The supporting structure for the bucks includes a yoke 38 having cylindrical guide members 39 slidably mounted in the bores 40 of the sleeves 34 and 35, but retained from rotation therein by splines 41 carried by the sleeve members.

55 Formed on the terminal arms 42 of the yokes are heads 43 having rectangular shaped grooves 44 for mounting horizontally arranged guide bars 45 and 46 having their ends projecting laterally from opposite sides of the yokes, the guide bars being retained in the grooves by set screws 47. Supported on the ends of the guide bars are the bucks 36 and 37 over which the shirts are extended as 60 later described.

65 The front bucks 36 include right and left sections 49 and 50 shaped to conform to the right and left sides of the shirt front, while the buck 37 includes spaced sections 51 and 52 conforming in 70 shape to the back of a shirt. Each section includes a horizontal plate portion 53 having a longitudinal rectangular groove 54 formed in its upper face and draining to a central sump 55 that is formed in a boss 56 depending from the lower face 75 of the plate, as best illustrated in Fig. 8. Formed

on the lower face of each plate and spaced to conform to the spacing of the guide bars 45 and 46 are pairs of ribs 57 and 58 for slidably engaging the side faces of the bars whereby the sections are guided for movement to and from each other as 5 later described.

The groove 54 is covered by a perforated plate 59 having its side edges supported on recessed shoulders 60 so that the top face of the plate aligns with the upper face of the plate portion of 10 the buck.

15 Yieldingly supported on the plate portion of the bucks by coiled springs 61 are perforated plates 62 for carrying a conventional padding material 63 retained by a covering that is sleeved over the outer edges of the bucks and secured to their inner edges by toothed clamping plates 63' (Figs. 15 and 16). The clamping plates 63' have slotted ears 63'' that are slidably retained on the bucks by fastening devices 64, the plates being urged into 20 clamping position by springs 64' sleeved on rods 64'' and having their ends engaging wing nuts 65 on the rods and against ears 65' on the bucks in which the rods are slidably mounted, as shown in Fig. 15.

25 The buck sections for the garment fronts move to and from each other for adjusting the collar portions of the shirts supported thereon relatively to the collar and neck band clamp later described, whereby shirts of different sizes are retained in 30 proper position to press closely around the neck band. The back buck sections are similarly movable but simply for the purpose of adjusting their size relatively to the back width of a shirt. To accomplish this movement, each yoke 38 carries a 35 tubular sleeve 66 threaded in a socket 66' formed in axial alignment with the guide post 39 to form a spindle for rotatably mounting vertically spaced gears 67 and 67' for the front bucks and a single gear 68 for the back buck.

40 Meshing with the respective gears 67 and 67' are rack bars 69 and 70, the rack bars being arranged at opposite sides of the respective gears and secured to the under face of the respective plate portions 53 of the bucks by bolts 71 extending 45 through spacing sleeves 72 whereby the racks are spaced a required distance below the plates to mesh with the gears.

46 The sections of the back buck are provided with similar rack bars that engage the teeth at opposite 50 sides of the single gear. In order to rotate the gears 67, 67' and 68, they carry laterally projecting rods 73, 74 and 75 respectively having sufficient length to project from under the bucks in easy reach of the operator.

55 It is thus apparent that the front buck sections are individually movable for the purpose of accommodating a variety of shirt sizes by manipulation of the rods 73 and 74, while the sections of the back are moved together by operation of the 60 lever 75.

65 In order to support the sleeves and that part of the garments not supported on the top of the bucks, I provide the yoke members 38 with laterally extending wings 76 and 77. The wings include slightly curved metal sheets having their inner edges fixed to the side edges of flanges 18 and 19 and their outer edges extending slightly beyond the outer end edges of the bucks as illustrated in 70 Fig. 2.

75 The flange portion 18 for the front bucks also provides a support for an upwardly curved bracket 80 having a tubular nave portion 81 forming a hinge element for pivotally mounting a collar and neck band clamp supporting plate 82.

The collar and neck band clamp supporting plate 82 is provided with ears 83 cooperating with the nave portion 81 to receive a hinge bolt 84 by which the rear of the plate is secured to the 5 bracket in substantially horizontal alignment with the upper faces of the pressing bucks. The plate 82 includes laterally extending arms 85 and 86 to which are secured track members 87 and 88 carrying neck band blocks 89 and 90 that 10 rest upon the bucks.

The neck band blocks are substantially quadrant shaped and have curved forward edges 91 conforming in shape to the inner front portions 15 of the neck bands of the shirts that are supported on the bucks.

It is thus apparent that the blocks 89 and 90 are loosely supported on the upper faces of the pressing bucks to permit adjustment of the 20 pressing bucks as above described.

20 Slidably mounted on the track members 87 and 88 are rectangular sleeve members 92 and 93 carrying laterally extending bosses 94 and 95 to which the ends 96 and 97 of neck band retaining loops 98 and 99 are secured. The loops 98 and 25 99 are preferably formed of resilient flat spring like metal and conform in shape to the front faces of the neck blocks as illustrated in Fig. 11.

The neck band loops are normally retained in yielding engagement with the front face of the 30 blocks by springs 100 that are positioned in recesses 101 formed longitudinally within the tracks 87 and 88 as illustrated in Fig. 13, one end of the springs bearing against the bottoms 102 of the recesses and the opposite end against pins 103 carried by the sleeve members 92 and 35 93 and extending through slots 104 formed in the track members.

It is thus apparent (Fig. 13) that the springs 40 retain the sleeve members 92 and 93 in retractive position with the forward inner face of the loops in clamping engagement with the blocks for clamping the front portion of the neck band and collar therebetween in locating the yokes of the shirts in proper position on the pressing bucks.

45 In order to move the neck band loops away from the blocks for the insertion of the shirt band, I provide a lever actuated mechanism now to be described.

Rotatably mounted in bearing openings 105 and 50 106 formed in the guide tracks 87 and 88 and in similar bearing openings 107, in lugs 108 and 109 projecting from the plate 82 is a horizontal shaft 110 having its ends extending beyond the track members. Fixed to the outer ends of the 55 shaft are cam disks 111 having their peripheries engaging against the rear ends of the sleeve members 92 and 93, Fig. 11. Also fixed on the shaft 110 intermediate the lugs 108 and 109 is a lever arm 112 whereby the shaft may be rocked to cause 60 the cam disks to move the sleeve members toward the pressing bucks, thereby moving the neck band loops away from the blocks 89 and 90.

In order to latch the neck band loops in released position, the tracks 87 and 88 carry latch 65 members 113 and 114, Figs. 11 and 12. The latch members include flat body portions 115 overlying the upper faces of the track members and having depending arms 116 and 117 straddling the track members and terminating in hooks 118 arranged 70 to enter recesses 119 in the sleeve members 92 and 93, and engage lugs 120. The latch members 113 and 114 are pivotally mounted on the track members by screws 121 extending through the arms 116 and 117 and into the sides of the track members.

The body portions 115 of the latches extend forwardly along the upper faces of the track members and carry depending pins 122 and 123 that are reciprocable through openings 124 in the respective track members. The latches are normally retained in position to engage the sleeve members by coiled springs 125 sleeved over the pins 122 and 123 and having their opposite ends engaging under the body portion of the latch members and the bottom of a recess 126 formed 10 in the track members, Fig. 13.

It is thus apparent that when the lever arm 112 is moved in a clockwise direction, Figs. 11 and 12, the eccentric disks will move the sleeve members into latching engagement with the latch members 113 and 114, which hold the neck band loops away from the neck band blocks, Fig. 12, against the stored up tension of the springs 100.

The latch members may be released by pressing on the heads 127 of the pins 122 and 123 20 which cause the hooks 118 to disengage the lugs 120, whereupon the springs 100 will shift the sleeve members to retracted position for drawing the neck band loops into engagement with the blocks 89 and 90.

To return the lever arms 112 to non-functional position, the shaft 110 is provided with coiled springs 128 and 129 having their ends engaging in apertures in the lugs 108 and 109 and in apertures formed in collars 130 fixed to the shaft. 30 When the lever is swung in a clockwise direction, the springs will wind about the shafts so that the stored up tension will retract the lever to non-functional position after the sleeve members have been moved into latching engagement.

The plates 82 include a forwardly extending portion 135 having upwardly extending lugs 136 and 137 to rotatably support a shaft 138 extending parallel with the shaft 110. Fixed on the ends of the shaft 138 at points directly over 40 the latch members are cam disks 139 and 140 for depressing the body portions of the latch members to automatically release them from engagement with the sleeve members later described. The shaft 138 also carries a lever arm 141 fixed 45 thereto in such a position that it will strike a stop on the ironing head later described. Loosely mounted on the shaft 138 adjacent the arm 141 is an eccentric disk 142 that is connected to the lever arm 112 by a link 143 and extending from 50 the face of the disk 142 is a pin 144 for a purpose later described.

Cooperating with the neck band clamp just described is a tail clamp 145, Figs. 1, 6 and 7, which includes a flat metal strip 146 having its ends 55 147 and 148 extending over the upper faces of the front buck sections to clamp the front edges of the shirts in taut condition over the bucks as illustrated in Fig. 7.

The strip 146 is pivotally carried on the upper 60 end of a vertical rod 149 that is yieldingly supported in a sleeve like bearing 150 carried by the flange 78 as best illustrated in Figs. 4 and 6.

The sleeve like bearing 150 is provided with an axial bore 151 to slidably mount the rod 149 65 and a counter bore 152 for guidingly mounting a collar 153 on the rod and for housing a coil spring 154 having one end engaging against the collar and its other end against the bottom of the counter bore to support the rod. The lower end 70 of the rod 149 is threaded as at 155 and fixed thereto is a laterally extending arm 156 which carries an upwardly extending guide pin 157 slidably mounted in an opening 158 in the flange 78 for preventing rotation of the rod 149.

The pivotal connection between the plate 146 and rod 149 includes depending ears 159 on the bottom of the plate engaging the sides of a cylindrical head 160 on the rod, a bolt 161 being extended through the ears and head to form the pivot. The rear edge 162 of the strip 146 is retained in clamping engagement with the upper faces of the bucks by a coiled spring 163 having one end hooked in an aperture 164 in the plate 10 and its opposite end fixed to a screw 165 carried by the flange 78.

To bridge the space between the sections of the back pressing buck, I provide a flat plate 168 having feathered side edges 169 overlying the upper 15 faces of the buck sections, Fig. 8, and which is supported to move with the padding material on the bucks by pins 170 and 170' depending from the under side of the plate and extending through 20 guide openings 171 formed in the yoke member 20 38 which supports the back pressing bucks.

The pins 170 and 170' carry coil springs 172 having their upper ends bearing against the plate and their lower ends against the yoke member to normally retain the plate in alignment with 25 the yieldable upper faces of the pressing buck sections. Upward movement of the plate is limited by nuts 173 threaded on the lower ends of the pins and engaging against stop shoulders 173' of the yoke member.

30. The bridge plate is preferably covered by a double faced flannel cloth 174 having its side edges overlapping the sides of the plate and the flannel 174 is covered by a cloth 175 having its side edges extending beyond the edges of the 35 flannel, shown in Figs. 8 and 15. This is an important feature in the construction of the back pressing bucks, since no creases or wrinkles are formed in a shirt that is pressed thereon.

30. The ironing head 176 is suspended from the lateral portion 16 of the upper header at a point between the posts 3 and 4, as now to be described.

Extending from the opposite side faces of the web 18 are annularly shaped brackets 177 and 45 178 carrying I-beam sections 179 and 180 that extend longitudinally of the lateral portion 16 of the header and below the lower flange 20 thereof, the I-beam sections being secured to the brackets by bolts 181 extending through the brackets 50 and upper flanges of the I-beam sections.

The ironing head includes a substantially rectangular shaped steam chest 182 having a lower pressing face plate 183 arranged to be engaged by the pressing bucks for the pressing of the garments therebetween. The upper face of the ironing head is provided with a raised portion 184 which is secured to the lower flanges of the I-beam sections by cap screws 185. Steam or the like may be admitted to the steam chest for heating the plate 183 as in ordinary practice through a pipe 186.

To raise the pressing bucks into engagement with the ironing head after they have been moved into position relatively thereto, the lateral portion 65 8 of the base member carries an air cylinder 187 having its axis located in vertical alignment with the axis of the guide posts 39 previously described, when one of the bucks is moved into pressing relation with the ironing head, Figs. 1, 4 and 5.

70. The cylinder 187 is supported on spaced parallel I-beam sections 188 extending transversely across the web 10 thereof to mount the lower head 189 of the cylinder. The upper portion of the cylinder is closed by a head 190 having a stuffing box 75 195 for slidably mounting a ram 196 having sub-

stantially the same diameter as the post 39 and which is mounted in substantially abutting relation therewith when in retracted position. Fixed to the lower end of the ram 196 is a piston 197 for actuating the ram when air is admitted to the lower side of the piston to cause the ram to engage and raise the post in its support, thereby lifting the pressing bucks into pressing engagement with the ironing head.

5 In order to admit the air for actuating the piston, the cylinder includes a valve chest 198 having a cylindrical bore 199 in which is slidably mounted a cylindrical valve member 200 arranged to reciprocate over an intake port 201 and over an aligning transfer port 202 that communicates the 15 valve chest with the interior of the cylinder.

The valve 200 is actuated by a rod 203 extending upwardly through a stuffing box 204 to a point above the head of the cylinder 187. Threaded onto the upper end of the rod are spaced stops 205 and 206 to be engaged by an actuating lever 207. The actuating lever 207 is pivotally mounted on ears 208 carried by the head 190 and has its forward end guided in a socket 209 formed in a 25 boss 210 on the cylinder head.

The lever 207 is retained in valve closing position by a spring 211 having one end bearing against the lever and the other against a cylinder head 189 to normally retain the valve in position 30 for closing the passage 202 to the cylinder. The lever 207 is automatically operated to open the passageway 202, when one of the pressing bucks is moved into functional position below the ironing head, as now to be described.

Extending from the bearing sleeves 34 and 35, 35 are bosses 212 having vertical cylindrical bores 213 opening from their lower ends, as illustrated in Fig. 2.

Slidably mounted in the bores 213 are plungers 214 which are normally retained in projected position by springs 215 each having one end bearing against the bottom of the bores 213 and its opposite ends against the plungers 214. The plungers 214 are retained in the bores by lateral pins 216 that move in slots 217 formed in the bosses 45 212 so that the pins, when they engage the lower ends of the slots, form stops to prevent displacement of the plungers.

Just prior to the time a buck is moved into alignment with the ironing head, the plunger for 50 that buck engages one of the inclined tracks 218 and 219 extending from opposite sides of the socket 209 so that the plungers are raised by the tracks against tension of their springs to drop into the socket 209 when the buck has reached its 55 aligning position with the ironing head. As soon as the plungers drop into the socket 209 they engage the projecting end of the lever 207 and rock the lever upon its pivot for shifting the valve 200 to open communication between the air supply 201 and the passageway 202 to the cylinder. When the valve opens communication to the air cylinder, the air acting on the under face of the piston 197 causes the ram 196 to lift the buck into engagement with the ironing head for pressing 60 the shirts on that buck.

A plunger 214, upon entering the socket 209, 65 also effects latching of the turret to prevent its rotative movement on the post 3 when the buck is being raised to pressing position.

After the shirt has been pressed, the lever 207 is rocked in the opposite direction to lift the plunger 214 from the socket 209 to permit movement of the bucks from under the ironing head.

This is accomplished by a foot lever 220 that is 70

5 pivotally mounted on a bracket 221 carried on the web 10 of the base portion 8 at a point adjacent the post 3. The pedal end 222 of the lever 220 extends forwardly of the base portion 8 in convenient position to the operator, Fig. 1.

The opposite end 223 of the lever is connected by a link 224 with a counter lever 225 having its central portion pivotally suspended from the under face of the web 10 by means of ears 226.

10 The opposite end of the counter lever 225 is connected by a rod 227 having its upper end extending loosely through an opening 228 in the end of the lever 202 and carries adjustable stops 229 which engage the upper face of the lever 207 when 15 the plunger 214 is in latched position, Fig. 2.

15 The foot lever 220 is yieldingly retained in functional position by means of a spring 230 sleeved over the link 224 and having one end bearing against the under face of the web 10 and its opposite end against the counter lever 225.

20 Thus, when the foot portion of the lever 220 is pressed downwardly, the counter lever 225 is rocked in reverse direction to move the rod 227 in a downward direction causing the stops 229 to 25 rock the lever 207 in a clockwise direction closing the valve 200 and lifting the plunger 214 from engagement with the socket 209.

25 Simultaneously with closing of the valve 200, the lever 225 actuates an exhaust valve 231, that 30 is operable in a valve chest 232 located at the opposite side of the cylinder from the valve chest 198 previously described. The air then escapes from the cylinder through a passageway 233 into the valve chest and through an exhaust port 234 to 35 atmosphere.

35 Upon release of air in the cylinder, the weight of the pressing heads and their support causes the ram to be moved into retracted position so that the pressing bucks may be moved from under 40 the ironing head upon operation of the turret by an actuating cylinder 235. The cylinder 235 is best illustrated in Figs. 2, 7 and 9 and is mounted on the base portion 8 in horizontal position with the axis thereof extending toward the axis of the 45 post 3. Slidably mounted in the cylinder is a piston 236 carrying a rod 237 slidable through a stuffing box 238 in the cylinder head 239. Rotatably carried on the outer end of the rod is a roller 240 arranged to engage the periphery of a cam 241 50 which is keyed to the hub portion of the turret by a spline 242, Fig. 2, and includes oppositely extending wing portions 243 and 244 having cam faces curved on radii eccentrically of the axis of the post 3 so that when the roller 240 acts on one 55 of the cam surfaces, the piston 236 will effect rotation of the cam to move the turret for carrying the pressing bucks to and from pressing position with the ironing head.

60 Air is admitted to the power side of the piston 236 through a valve 245, Fig. 9, which is operable in a valve chest 246 forming a part of the cylinder 235. The valve 245 moves over a port 247 communicating the valve chest with the cylinder 235, Fig. 7, and through which air is delivered to 65 and from the cylinder depending upon the position of the valve 245 relatively to an intake port 248 and an exhaust port 249 located at opposite ends of the valve chest.

70 The piston 245 is operable by a rod 250 complementary to the rod 251 of the exhaust valve, previously described, and has its lower end connected to an arm 252 extending laterally from the lower end of the rod 251. The valves 245 and 231, therefore, operate together, and are so located 75 relatively to their respective ports that when the

exhaust valve is open, the valve 245 is in position to allow admittance of air to the power side of the cylinder 235 to cause rotative movement of the turret and when the exhaust valve is closed, the valve 245 is in position to allow the air in the cylinder 235 to escape through the port 249. The exhaust valve 231 is positioned to open in advance of the valve 245 to allow the bucks to be lowered before the turret starts to revolve.

5 The cam faces 243 and 244 and the effective 10 stroke of the pistons 236 are such as to rotate the turret through an arc of substantially 90 degrees, but the momentum of the turret causes its complete movement through an arc of 180 degrees to move the other buck into position under the 15 ironing head.

The coasting movement of the turret causes the roller 240 to engage the other cam face to move the piston 236 into retracted position to allow the air to exhaust through port 249, thereby resetting the piston for effecting reverse rotation of the turret when the valves are again actuated.

20 In order to retain the valve 231 in exhaust position, and the valve 245 in position to continue admission of air to the cylinder 235 until the turret has rotated through 90 degrees, I provide the foot lever 220 with a holding latch 253 which is illustrated in detail in Fig. 10, the latch 253 being pivotally supported on a lug 254 mounted on the web 10 of the base portion 8 and is normally retained away from the lever and against a cam disk 255 having high lobe portions 256 and 257 located substantially 90 degrees apart and low lobe portions 258, 259 and 260 at the 30 35 opposite sides of the high lobe portions to provide dwells whereby the latch is out of the path of the lever 220 so that the lever may be actuated without interference of the pawl when either of the pressing bucks are in pressing position.

40 The latch 253 includes a hook portion 261 adapted to engage over the lever as soon as the turret starts to rotate under influence of air in the cylinder 235, but as soon as one of the low points of the cam aligns with the pawl, the 45 spring 262 withdraws the pawl from engagement with the foot lever to allow the spring 230 to rock the counter lever 220 and reverse the position of all of the valves.

45 In order to prevent damage to one of the neck 50 band loops, when the front pressing bucks are moved into alignment with the ironing head, in case the operator fails to return it to clamping engagement with one of the neck band blocks, I provide a T-shaped arm 265 located on the 55 ironing head and projecting therefrom directly in the path of travel of the lever 141.

55 Just prior to the time the neck band loops are carried into position relative to the ironing head, the lever 141 will rock the shaft 138 to release 60 the latches 113 and 114 and permit retractive movement of the loops in response to the springs 100.

65 I also provide means for automatically releasing the neck band loops when the front pressing bucks move away from the ironing head.

This is accomplished by a spring pressed pawl 266 pivotally mounted on the bracket 267 carried by the arm 265, Fig. 1, so that when the pawl 70 engages the pin 144 on the disk 142, the lever 112 is rocked by means of the link 143 to rotate the shaft 110 and move the sleeve members into position to be engaged by the latches 113 and 114.

75 The mechanism for pressing the collars and 75

cuffs of a shirt is mounted on the base portion 9 and the portion 17 of the header 7.

This mechanism includes a turret 270 of substantially the same construction as the turret 5 previously described, except that the arms 271, complementary to the upper arms of the body pressing turret support parallel beams 272 and 273 which carry the cuff pressing bucks 274, gusset pressing bucks 275 and collar and yoke pressing bucks 276 and 277. The pressing bucks 274 and 275 cooperate with the ironing heads 278 and 279, and the pressing bucks 276 and 277 with an ironing head 280 that are supported on the header portion 17 of the frame, as clearly illustrated in Fig. 1.

The actuating mechanism for the turret and the controls thereof are substantially identical to the similar parts of the body pressing mechanism, and therefore, need not be described in 20 detail.

In order to draw moisture from the padding of the pressing bucks, the sumps 55 communicate with the pipe sections 282 and 282' carried by T-fittings 283 that are connected to the upper end of the nipples 64, the ends of the sections telescoping into collars 284 formed integrally with the bucks.

The post portions of the supporting yokes are provided with channels 285 having their upper 30 ends communicating with the nipples and their lower ends communicating with a conduit 286 carried by the turret and which in turn communicates with a vertical duct 287 formed in the post 3. The lower end of the duct 287 is connected through an annular manifold 288 with a pipe 289 leading to a vacuum pump 290, the vacuum pump being actuated by a suitable motor 291, mounted on the portion of the base between the posts 7, 8 and 13, as best illustrated in Fig. 1.

40 The pressing buck 274, 275, 276 and 277 may be provided with similar drainage channels which are connected to the vacuum pump by a conduit 292.

In operating a machine constructed and assembled as described, an operator stands adjacent the turret carrying the cuff, gusset, yoke and collar pressing bucks and places shirts thereover, as shown in Fig. 14, the yoke (a) of one shirt being spread over the buck 277 and the gussets (b) of that shirt over the bucks 275, while the collar (c) of the other shirt is spread over the buck 276 and the cuffs (d) over the bucks 274. The turret is then operated to carry the shirts in pressing relation with the ironing heads 55 278, 279 and 280. While the cuffs, gussets, yoke and collar are being pressed, the operator applies two more shirts to the other set of bucks on the turret to be moved to pressing position upon return movement of the turret to remove the shirts.

60 After the cuffs, gussets, yokes and collars have been pressed, the shirts are then reversed on the respective bucks, so that the unpressed cuffs and collar of one shirt and the unpressed gussets and yoke of the other shirt will be pressed upon the 65 next operation of the turret to complete these portions of the shirt. The shirts are then delivered to a second operator who stands in front of the shirt body pressing turret at a point adjacent the control levers 13 and 14 and the foot operating pedal 222 and who then presses the 70 bodies of the shirts.

The complete left front (e) of one shirt is spread over the pressing buck 50 and the right front (f) of the second shirt is applied over the 75 pressing buck 49 with their side seams (g), Fig.

7, closely engaging the outer longitudinal edges of the bucks.

The levers 13 and 14 are then actuated to position the bucks to the size of the shirts so that the front neck band portions (h) thereof are directly engaging against the curved faces of the neck band blocks 89 and 90, after which the operator presses the head 127 of the pins to release the latch members 113 and 114 from engagement with the sleeves 92 and 93 which carry the neck band loops 98 so that the springs 100 draw the neck band loops into clamping engagement with the blocks 89 and 90 to clamp the neck band portions of the shirts therebetween, as clearly illustrated in Fig. 11.

The tails of the shirts are then drawn under the ends 147 and 148 of the tail clamping member to retain the button hole strip and button pleat strip "D" and "E" of the shirts in taut condition on the bucks.

The remaining body portions of the shirts, including the sleeves, are then placed upon the supporting aprons 16 and 17 carried by the front buck supporting yoke member 38.

The operator then depresses the foot pedal 222 to rock the counter lever 225 in a clockwise direction, Fig. 2, to cause the rod 221 to rock the lever 207 for raising the plunger 214 out of engagement with the socket 209 to release the turret.

Movement of the counter lever 225 also actuates 30 the valve 246 to admit air under pressure to the power side of the piston 236 to cause the roller 240 to act on the cam wing 244 and effect rotation of the turret in an anti-clockwise direction, Fig. 7.

When the foot lever is depressed and the turret begins to rotate, the cam 257 will move the pawl 253 into engagement with the foot lever and hold it in depressed position until the low lobe portion 259 of the cam comes into alignment with 40 the pawl.

At this time the spring 262 moves the pawl out of latching engagement with the foot lever so that the foot lever is returned to its normal position under influence of the spring 238 which also 45 rocks the counter lever 225 in the opposite direction shutting off flow of air to the cylinder 235 and opening exhaust through the port 249.

The momentum of the rotating turret will cause the cam portion 243 to move the piston in 50 retracted position and expel the air from the cylinder.

The plunger 214 for the back pressing bucks will then ride up the cam track 218 and latch in the socket 209 to stop rotation of the turret.

The shirts applied to the front pressing buck are then in position directly under the ironing head.

As soon as the plunger 214 drops into the socket 209, the lever 207 will be rocked, thereby actuating the valve rod 203 and opening communication between the air supply pipe 201 and the port 202 leading to the power side of the piston 197. Air admitted to the cylinder raises the piston to cause the ram 196 to engage the post 39 for raising the pressing bucks into pressing relation with the ironing head.

This movement of the lever 207 does not effect operation of the counter lever, since the free end thereof moves loosely over the rod 227.

The back of a third shirt is then spread over the back pressing bucks 51 and 52 and the pressing bucks are adjusted to the width of the shirt by actuating the rod 75.

The operator then presses the foot pedal to 75

effect lowering of the front pressing bucks by shutting off the air supply to the pressing cylinder 190, opening the exhaust valve 231 and the valve 249 which admits air to the turret actuating cylinder 235. This movement also releases the turret for rotation by the actuating cylinder, but in the reverse direction, for the reason that the roller 240 is then engaging the cam wing 243 so that the turret moves in a clockwise direction, Fig. 7, in returning the front pressing bucks to the operator's position and the back pressing buck into alignment with the ironing head.

As soon as the plunger 214 of the back pressing bucks drops into the socket 209, the lever 207 will actuate the valve 200 for admitting the air to the cylinder 190 for raising the back pressing bucks into pressing relation with the ironing head.

The fronts of the shirts on the front pressing bucks are reversed and replaced over the pressing bucks as previously described, to iron the left and right fronts of the respective shirts, after which the front pressing bucks are moved into pressing engagement with the ironing head and the back pressing bucks are moved into position for removing the shirt therefrom.

Another shirt is then placed over the back pressing bucks, as previously described.

Moisture passing into the paddings of the respective bucks is drawn therefrom by the vacuum pump 290.

Should the operator fail to release the neck band clamps, the lever 141 will engage the stop member 265 on the ironing head to effect automatic engagement of the neck band clamps so that they will not be crushed by the pressing bucks and the ironing head when the pressing bucks are moved into engagement therewith.

When the front pressing bucks move away from the ironing head, the pawl 266 will engage the pin 144 on the disk 142 to rock the lever 112 which automatically latches the neck band loops in released position so that the shirts may be removed.

From the foregoing, it is obvious that with the machine in operation the equivalent of one complete body of a shirt is ironed upon each operation of the machine.

What I claim and desire to secure by Letters Patent is:

1. In a pressing apparatus of the character described, a support, an ironing head mounted on the support, a pressing buck, means for movably mounting the pressing buck on the support whereby the pressing buck is moved to and from pressing relation with the ironing head, garment clamping means carried by the pressing buck, and release means on the ironing head engaging said clamping means for effecting release of said clamping means upon movement of the buck from said ironing head.

2. In pressing apparatus of the character described including a support, an ironing head mounted on the support, a pressing buck, means for movably mounting the pressing buck on the support for movement to and from pressing relation with the ironing head, garment clamping means carried with the pressing buck, clamping and releasing means for actuating said garment clamping means, means for rendering said clamping means effective when the pressing buck is moved into pressing relation with the ironing head, and means on the ironing head for rendering said clamping means ineffective when the pressing buck is moved from said ironing head.

3. In a pressing apparatus of the character described, a support, a pair of pressing buck sections, a separate garment clamp individual to each of said pressing buck sections and carried on the support between said sections, and means for movably mounting the pressing buck sections on the support for adjusting the pressing buck sections to and from said garment clamping means.

4. In a pressing apparatus of the character described, a support, a pair of laterally spaced pressing bucks, a garment clamp associated with each of said pressing bucks, means for movably mounting the pressing bucks on the support for movement to and from each other to adjust the pressing bucks relatively to said garment clamping means, an ironing head on the support, means for moving the pressing buck to and from pressing relation with the ironing head, and means on the ironing head controlling said clamping means.

5. In a pressing apparatus of the character described, a support, a pair of pressing buck sections, a clamp associated with each of said pressing buck sections to clamp the neck band of a garment for positioning garments on said sections, a tail clamp cooperating with the first named clamps to stretch the garments, and means for movably mounting the pressing buck sections on the support for adjusting said sections relatively to said garment positioning clamps.

6. In a pressing apparatus of the character described, a support, an ironing head carried by the support, a pair of pressing buck sections, a garment clamp associated with each of said sections, means for mounting the pressing buck sections on the support for movement to and from the ironing head, and means for adjusting the pressing buck sections relatively to said garment clamping means for accommodating garments of different size, whereby one half of the front portions of two different size garments are pressed by the ironing head upon each movement of the pressing buck sections under the ironing head.

7. In a pressing apparatus of the character described, a support, a pair of pressing buck sections, a garment clamp associated with each of said pressing buck sections, means for movably mounting the pressing buck sections on the support for adjustment relatively to said garment clamping means, an ironing head on the support, means for moving the pressing buck sections to and from pressing relation with the ironing head, and means operable incidental to movement of the pressing buck sections for effecting actuation of said garment clamping means.

8. In a pressing apparatus of the character described, a supporting frame, an ironing head mounted on the supporting frame, a turret including radially extending arms, means for rotatably mounting the turret on the supporting frame, pressing bucks, means for mounting the pressing bucks on said arms for movement in a direction toward the ironing head when vertically aligned therewith, opposed cam members on the turret, an actuator on the supporting frame engaging with said cam members for oscillating the turret to bring the pressing bucks into alternate alignment with the ironing head, and means on the supporting frame for raising the pressing bucks into pressing engagement with the ironing head.

9. In a pressing apparatus of the character described, a supporting frame, an ironing head

mounted on the supporting frame, a turret rotatably mounted on the supporting frame, garment pressing bucks, means for mounting the garment pressing bucks on the turret, means on the supporting frame for raising the pressing bucks, means on the supporting frame for effecting oscillation of the turret to alternately move the pressing bucks into pressing relation with the ironing head, means carried by the turret for latching the 5 turret against movement when one of the pressing bucks is in alignment with the pressing head, means for rendering said raising means effective, and actuating means connected with said last named means and operable by the latching means 10 to raise the pressing bucks.

10. In a pressing apparatus of the character described, a support, a pair of pressing buck sections, a neck band clamp associated with each of said pressing buck sections, a tail clamp cooperating 20 with the neck band clamps to retain garments on the pressing buck sections, and means adjustably mounting the pressing buck sections on the support for adjusting the sections relatively to said neck band clamps for accommodating 25 the fronts of two different size garments.

11. In a pressing apparatus of the character described, a supporting frame, an ironing head mounted on the supporting frame, a pair of spaced garment pressing bucks, means for adjustably 30 mounting the garment pressing bucks on the frame for movement to and from each other to accommodate garments of different sizes, a bridge plate yieldingly supported on the pressing bucks for bridging the space therebetween, and a plurality 35 of layers of cloth carried by the bridge plate and having different degrees of overlap on the pressing bucks.

12. In a pressing apparatus of the character described, a support, a pair of pressing buck sections mounted on the support, means for moving the pressing buck sections to and from each other, a bridge member yieldingly supported for movement 40 in the direction of the plane of the pressing buck sections, and means for effecting movement 45 of the pressing buck sections to and from the bridge member for accommodating the buck sections to garments of different sizes.

13. In a pressing apparatus of the character described, a support, pairs of pressing buck sections having yieldable pressing surfaces, means movably mounting the pressing buck sections on the support for lateral movement to and from each other, a bridge member yieldingly supported between the pressing buck sections for movement with the yieldable pressing surfaces, actuating means for effecting movement of the pressing buck sections to and from the bridge member 10 for accommodating backs of garments of different sizes, and a plurality of layers of sheet material carried by the bridge member and having different degrees of overlap on the pressing buck sections for preventing creasing of the garments 15 at the juncture of the bridge member with the pressing buck sections.

14. In a pressing apparatus of the character described, a support, a pair of pressing buck sections mounted on the support, a bridge plate having feathered side edges resting on adjacent side edges of the pressing buck sections, a double faced cloth carried by the bridge plate and having edges overlapping the pressing buck sections beyond the feathered edges of said plate, a second cloth having edges overlying the buck sections to a greater extent than do the edges of the double faced cloth, and means for moving the buck sections to and from each other to accommodate 20 garments of different sizes.

15. In a pressing apparatus of the character described, a support, a pair of pressing buck sections mounted on the support for movement to and from each other, padding on the pressing buck sections, a bridge plate having feathered side edges resting on the padding at adjacent sides of said bucks, a plurality of layers of cloth carried by the bridge plate and having different degrees of overlap on the padding, and means yieldingly retaining the bridge plate in central position on 35 the support between said pressing buck sections and for movement in the direction of the plane of the pressing buck sections.

ARCHIE O. LONG. 45
